UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

DRIVING MECHANISM FOR TYPOGRAPHICAL MACHINES.

1,231,905.

Specification of Letters Patent.

Patented July 3, 1917.

Application filed July 11, 1914. Serial No. 850,326.

To all whom it may concern:

Be it known that I, DAVID S. KENNEDY, a citizen of the United States, residing at Brooklyn, in the county of Kings and State 5 of New York, have invented certain new and useful Improvements in Driving Mechanism for Typographical Machines, of which the following is a specification, reference being had therein to the accompanying drawing.

My invention relates to typographical machines, as for instance linotype machines of the general organization set forth in U. S. Letters Patent to O. Mergenthaler, No. 15 436,532, wherein the matrices as they are released from the magazine pass to assembling devices, such as the assembler belt and star wheel, whereby in turn they are delivered to the further assembling mechanism. More particularly, it relates to the 20 means for driving or actuating the said assembling devices, the construction and mode of operation of the improvements being described in the following specification 25 and finally pointed out in the claims.

In the accompanying drawings, I have shown my invention only in preferred form and by way of example, and as applied to a particular style of machine, but obviously 30 many changes and variations may be made therein, and in its mode of application, which will still be comprised within its spirit. Similarly, it may be applied to other 35 forms of typographical machines, such as typesetters, typecasters and the like, which are designed to handle type or dies, instead of matrices. Generally speaking, I desire 40 it to be understood that I do not limit myself to any specific form or embodiment, except in so far as such limitations are specified in the claims.

Referring to the drawings:

Figure 1 is a front view of a portion of a linotype machine, with my invention embodied therein;

Fig. 2 is a detached perspective view of the improved arrangement;

Fig. 3 is a detached view of the supporting bracket; and

Fig. 4 is a section on the line 4-4 of Fig. 2.

As in the said Mergenthaler patent, the machine is equipped with suitably actuated assembling devices, such as the belt A and 55 star wheel A¹, shown respectively by full

and dotted lines in Fig. 1. Both are driven by suitable connections from the shaft B, which is provided with the fast and loose pulleys B¹, to which motion is imparted by the endless belt C, the latter being under 60 the control of the belt shifter B². The parts so far described and their mode of operation, except as hereinafter set forth, are or may be of any approved or desired form, and in themselves constitute no part of my 65 present invention.

The belt C is actuated from the power shaft D and grooved pulley E thereon, and one of the principal features of my invention is the arrangement of the guide pulleys etc. between the pulleys E and B¹, and their mode of mounting. The opposite stretches of the belt toward and from the pulley E pass respectively around the upper and lower guide pulleys F and G, which 70 are located in substantially the same vertical plane with the pulley E. These two belt stretches between the pulleys F and G and the pulley B¹, pass in opposite directions 75 around a single idle or guide pulley arrangement H, the latter being located in the same plane with the pulley B¹, and at substantially right angles to the plane of the pulleys E, F, G.

It will be noted that the pulley arrangement H is formed with two circumferential grooves H¹ to receive the respective stretches and hold them out of contact at their point of crossing. This feature is of importance 85 in that it eliminates the friction and wear 90 due to the contact of the crossed belt in previous constructions, and also the objectionable slipping and running of the belt off the pulleys is substantially prevented. It will similarly be noted that the journals 95 of all the pulleys are not horizontal, thereby minimizing the liability to escape of the lubricant. These and other advantages are inherent in the improved construction. It will be understood, of course, that the pulley arrangement H might be made up of two 100 independently rotatable sections instead of their being joined together as an integral structure as shown in the drawings, the idea of the invention in this respect being 105 to provide a pulley arrangement having two grooves in which the opposite stretches of the belt engage, as before described.

As a convenient means of mounting the pulleys F, G, and H, which are intermediate 110

the driven pulley B^1 and the driving pulley E , I preferably support them on the detachable bracket J , which is formed with a journal J^1 for the pulley H , and with two rearwardly-extending arms J^2 and J^3 provided with journals J^5 and J^6 for the pulleys F and G respectively. The bracket J is also formed with the rearwardly projecting member or arbor J^4 , which may be readily engaged in or disengaged from the corresponding socket or recess in the main frame.

As previously stated, I have shown my invention only in preferred form and by way of example, and as applied to the particular form of assembling devices noted. However, many modifications and alterations therein, and in its mode of application, will suggest themselves to those skilled in the art, without departure from its scope.

Having thus described my invention, its construction and mode of operation, what I claim and desire to secure by Letters Patent of the United States, is as follows:

1. The combination of a movable member, and driving means therefor, the said means comprising a driving pulley, and a driven pulley, both rotating about horizontal axes, a belt connecting said pulleys with its opposite stretches crossing each other, and a system of guiding pulleys also rotating about horizontal axes and acting to maintain the stretches of the belt separated from each other to prevent contact at the point of crossing.

2. The combination of a movable member, and driving means therefor, the said means comprising a driving pulley, a driven pulley, a belt connecting said pulleys with its opposite stretches crossing each other, and belt guiding means including an idle pulley arrangement having two grooves in which the opposite stretches of the belt engage, and whereby they are held out of contact at the point of crossing.

3. The combination of a movable member, and driving means therefor, the said means comprising a driving pulley, a driven pulley, a belt connecting said pulleys with its opposite stretches crossing each other, an idle pulley arrangement having two grooves in which the opposite stretches of the belt engage, and whereby they are held out of contact at the point of crossing, and two guiding pulleys arranged between the driving pulley and the idle pulley and about which the opposite stretches of the belt travel.

4. The combination of a movable member and driving means therefor, the said means comprising a main driving pulley E , a driven pulley B^1 , a system of intermediate pulleys F , G , H , and a belt C arranged to travel beneath the pulley G , up over the pulley arrangement H , around the driven

pulley B^1 , back beneath the pulley arrangement H , up over the pulley F , and finally around the driving pulley E .

5. The combination of a movable member, and driving means therefor, the said means comprising a driving pulley, a driven pulley, a belt connecting said pulleys, an intermediate idle pulley arrangement H and guiding pulleys F , G , about which the belt travels, together with a detachable supporting bracket upon which the pulleys F , G , H are mounted.

6. The combination of a movable member, and driving means therefor, the said means comprising a driving pulley, a driven pulley, a belt connecting said pulleys, an intermediate idle pulley arrangement H and guiding pulleys F , G , together with the supporting bracket J provided with the journal J^1 for the idle pulley arrangement and journals J^5 and J^6 arranged at right angles to the journal J^1 and upon which the guiding pulleys are mounted.

7. The combination of a movable member, and driving means therefor, the said means comprising a driving pulley, a driven pulley, a belt connecting said pulleys, an intermediate idle pulley arrangement H and guiding pulleys F , G , together with the supporting bracket J for the pulleys F , G , H , and having the member J^4 adapted to be detachably secured in the framework.

8. The combination of a movable device, with driving means therefor, the said means comprising a driving pulley, a driven pulley, a belt connecting said pulleys, an intermediate idle pulley arrangement H and guiding pulleys F , G , together with a supporting bracket J carrying the idle pulley H and formed with rearwardly extending arms J^2 , J^3 , upon which the guiding pulleys F , G , are respectively mounted.

9. The combination of a movable device, with driving means therefor, the said means comprising a driving pulley, a driven pulley, a belt connecting said pulleys, an intermediate idle pulley arrangement H and guiding pulleys F , G , together with a supporting bracket J carrying the idle pulley H and formed with rearwardly extending arms J^2 , J^3 , upon which the guiding pulleys F , G , are mounted, and formed further with a rearwardly extending arbor J^4 by which said bracket is secured to the framework.

10. The combination of a movable member, and driving means therefor, the said means comprising the driving pulley E , the driven pulley B^1 arranged to rotate in a plane at right angles to that of the pulley E , a belt connecting said pulleys, and the system of intermediate pulleys F , G and pulley arrangement H about which the belt travels, the pulley arrangement H having two grooves wherein the opposite stretches of the connecting belt engage and being ar-

ranged to rotate in the plane of the driven pulley B¹, and the pulleys F and G being arranged to rotate in the plane of the driving pulley E.

- 5 11. The combination of a movable member and driving means therefor, the said means comprising a driving pulley, a driven pulley, a belt connecting said pulleys, and a system of intermediate grooved guiding pulleys F and G and pulley arrangement H, the pulley arrangement H having two grooves wherein the opposite stretches of the belt engage, and the pulleys F and G being dis-

posed at right angles to the pulley arrangement H and located on opposite sides thereof and in such position that the portions of the belt passing between the several pulleys will travel in substantially vertical parallel lines situated in the planes of the respective grooves of the pulley arrangement H. 15

In testimony whereof, I have affixed my signature in presence of two witnesses.

DAVID S. KENNEDY.
